UNITED STATES PATENT OFFICE.

JAMES L. COFFEY, OF MILWAUKEE, WISCONSIN.

CANDY-BOX HOLDER.

Application filed May 3, 1923. Serial No. 636,329.

To all whom it may concern:

Be it known that I, JAMES L. COFFEY, a citizen of the United States, residing at Milwaukee, county of Milwaukee, and State of

Wisconsin, have invented new and useful Improvements in Candy-Box Holders, of which the following is a specification.

My invention relates to improvements in candy box holders. Modern candy boxes are highly ornamental, and in many cases the ornamentation (particularly of the cover) discloses a high degree of artistic merit. The object of this invention is to provide means whereby such ornamental covers may be supported by a suitable holder in a position and under conditions whereby the contents of the box may be simultaneously displayed, and protected from dust, flies, and other sources of contamination and their fresh appearance preserved.

It is also an object of this invention to provide means for displaying and protecting the contents of a candy box and also displaying the cover in such relation thereto as to disclose the title, the trade marks, the name of the manufacturer, and any other indica appertaining thereto, the cover and the box holder acting in combination to produce a highly ornamental and attractive display calculated to advertise the product and promote sales.

In the drawings:

Figure 1 is a perspective view of a candy box holder embodying my invention, with the box cover in position for display.

Figure 2 is a sectional view drawn on line 2-2 of Figure 1.

Figure 3 is an end view.

Like parts are identified by the same reference characters throughout the several views.

The box holder comprises an open ended casing or rectangular frame having a bottom wall 1, front and back walls 2, and a top wall 3, the latter having an elongated window or sight opening 5 to which a sheet of mica, glass, or other transparent material 6 is applied from the under side and secured to the marginal portions of the top wall 3, as clearly shown in Figure 2. At the ends of the top wall 3 is provided with a downwardly folding flap 7 in hinged connection with the top wall along its upper margin. Where the box is formed of paper or similar material, the hinge may be formed by creasing the material in such a manner that

the flap will fold or swing downwardly about the crease line as an axis. These crease hinges are well known to the art of paper box manufacture.

It is not essential that both ends of the box be open but they are preferably so constructed, whereby a candy box 8 of appropriate size may be inserted into the holder from either end by raising the flap 7 at that end. After the box has been inserted the flap 7 swings downwardly to close and darken any opening that may exist between the top of the box and the top 3 of the holder, thus preventing flies from obtaining access to the space underneath the mica or glass window 6.

The margins of the sight opening 5 may be cut to any desired ornamental contour. The bottom 1 may also be partially cut away and the partially cut-away portion folded downwardly and backwardly to form a brace 10 adapted to support the box in an inclined position.

The cover supporting lid frame 12 has a crease hinge connection with the rear margin of the top 3 and the back wall 2. This frame 12 may also be formed integrally with the cover 3 or the wall 2 and the material creased to allow the frame to swing to a folded position on the top of the holder or to a raised backwardly inclined position for cover display purposes, as illustrated in Figures 1 and 2. This frame has an opening adapted to receive the cover flanges 13. The top 14 of the cover projects beyond these flanges so that the cover cannot pass through the opening, although the flanges are received therein and constitute the means whereby the frame supports the cover in position for display.

In the construction shown, the cover is provided with a ribbon, knotted in the form of a bow for ornamental purposes, and the ends of the ribbon are passed over the margins of the top of the cover and of the cover flanges 13, the extremities being inturned and gummed to the interior surfaces of said cover flanges. The portions 16 of the ribbon are stretched across the space between the associated margins of the top of the cover and its flange. These portions 16 of the ribbon bear frictionally and under tension against the margins of the frame when the cover flanges are inserted through the opening, thereby assisting in preventing the cover from falling forwardly from the frame in

case the frame should be moved or jarred accidentally.

The back wall 2 of the holder preferably has an upwardly extending portion 17 which laps upon the cover supporting frame 12 and serves as a brace to limit the backwardly swinging movement of the frame. The effectiveness of this brace may be increased by providing the portion 17 with upwardly extending arms 18 at its respective ends which lap upon the end bars of the frame along the ends of the cover receiving opening. These bracing portions 17 and 18 are adapted to hold the frame in nearly a vertical position but with a sufficient backward inclination to avoid any tendency for the cover to fall out under normal conditions. The retentive action of the ribbon is therefore unnecessary except under abnormal conditions, and it is even then regarded as merely a desirable but not as an essential feature, the principal purpose of the ribbon being that of ornamentation on the face of the box cover.

25 I claim:

1. A holder for a candy box and a wholly detachable cover having marginal flanges, said holder comprising an inclined body portion with open ends adapted to receive said box, and a frame extending upwardly

and rearwardly from said body portion and provided with a rectangular opening corresponding substantially in form and area to the part of the cover bounded by flanges thereof, whereby said flanges are receivable through said opening to support said cover above and in a detached relation to said box.

2. A paper candy box holder comprising the combination of a rectangular open ended enclosure provided with downwardly folding end flaps depending from the top of said enclosure, a cover supporting lid portion in crease hinge connection with the rear upper margin of the enclosure, and extension flaps 45 on the rear wall of the enclosure adapted to facilitate supporting the lip portion in an inclined cover supporting and displaying position.

3. A holder for a candy box, said holder comprising a single piece of flexible material bent to form a casing adapted to receive a candy box and a frame adapted to support the cover of said candy box, said casing having an open top and sides and a cut-out portion in its bottom adapted to support said casing in an inclined position, the frame being apertured to receive the flanges of a box cover.

JAMES L. COFFEY.
